[57] CLAIM

The ornamental design for a fishing lure, as shown and described.

DESCRIPTION

FIG. 1 is a perspective view of my fishing lure, taken generally from the bottom of the lure;

FIG. 2 is a perspective view of the lure, taken generally from the top;

FIG. 3 is a side elevational view of the lure, with the opposite side being a mirror image thereof;

FIG. 4 is a front plan view of the lure; and,

FIG. 5 is a rear plan view of the lure.
